U. VOSMEK

REAR SIGHT FOR RIFLES

Filed April 6, 1923

FIG. 1.

FIG. 2.

FIG. 3.

FIG. 4.

FIG. 5.

Inventor
Ulrich Vosmek

By

J. W. Bryant
Attorney.

UNITED STATES PATENT OFFICE.

ULRICH VOSMEK, OF ANTIGO, WISCONSIN.

REAR SIGHT FOR RIFLES.

Application filed April 6, 1923. Serial No. 630,304.

To all whom it may concern:

Be it known that I, ULRICH VOSMEK, a citizen of the United States of America, residing at Antigo, in the county of Langlade 5 and State of Wisconsin, have invented certain new and useful Improvements in Rear Sights for Rifles, of which the following is a specification.

This invention relates to certain new and 10 useful improvements in gun sights, and has particular reference to the rear sight and the laterally variable mounting thereof permitting laterally shifting movement of the rear sight relative to the gun barrel and front sight with a vertical screw adjustment operating in lieu of the usual step by step 15 elevator.

The primary object of the invention resides in the provision of a laterally variable 20 rear sight for gun barrels wherein a micrometer adjustment thereof is rendered possible through the provision of a rack and pinion construction permitting minute adjustment thereof compensating for faulty 25 mountings or displacement.

With the above and other objects in view as the nature of the invention is better understood, the same consists of the novel form, combination and arrangement of parts 30 hereinafter more fully described, shown in the accompanying drawing and claimed.

In the drawing, wherein like reference characters designate corresponding parts throughout the several views,

35 Figure 1 is a top plan view of a laterally variable gun sight constructed in accordance with the present invention, the same being illustrated as operatively positioned upon the barrel of a gun that is shown by dotted lines,

Figure 2 is a side elevational view of the sight,

Figure 3 is a longitudinal detail view taken on line III—III of Fig. 1 showing the 45 set screw for retaining the variable sight in its adjusted position and the elevating screw for the sight arm,

Figure 4 is a detail cross sectional view taken on line IV—IV of Fig. 1, and

50 Figure 5 is a perspective view of the laterally variable or adjustable sight.

Referring more in detail to the accompanying drawing, the reference numeral 1 designates an elongated sight arm carrying 55 a depending dove-tail-shaped lug 2 extending transversely of the forward end thereof

for anchoring in the upper side of a gun barrel 3 illustrated by dotted lines in Figs. 1 and 2, the sight arm 1 being rigidly mounted upon the gun barrel against laterally shifting movement in the usual manner.

A vertical screw adjustment associated with the rear end of the sight arm 1 operates in lieu of the usual step by step elevator mechanism, a set screw 4 being threaded 60 through the rear end 5 of the sight arm with the lower end 4a thereof adapted for engagement with the upper face of the gun barrel as shown in Fig. 2 for obtaining the proper elevation of the rear end of the sight arm. 65 This screw adjustment permits extremely fine variations in vertical movement of the rear end of the sight arm and is more accurate than the step by step elevating mechanism. 70

The laterally adjustable or variable sight embodies a base plate 6 preferably rectangular in plan view with slightly rounded ends as shown in Figs. 1 and 5, the upper opposite side edges of the base plate 6 being chamfered as at 7 to provide side ribs 8 and 9 while a perpendicular sight wall 10 projects upwardly and centrally of the base plate 6 with the forward face thereof concaved at 11 while the upper edge intermediate its ends has a sight groove 12. A series of rack teeth 13 are formed on the forward rib 9 at the edge thereof for purposes presently to appear. 75

The rear end 5 of the sight arm 1 is constructed for transversely and slidably supporting the base plate 6 of the rear sight wall 10, the rear end 5 being cutaway to provide a transverse seat 14 having front and rear overhanging ledges 15 and 16 respectively that confine the ribs 9 and 8 as 80 illustrated in Fig. 3.

An adjustment screw is associated with the forward end of the enlarged rear portion 5 of the sight arm and the rack teeth 13 upon the rib 9, the adjusting screw embodying a disk head 17 rotatably seated in the socket 18 formed in the forward end of the rear end side, the screw head 17 being 85 provided with a kerf 19 in its upper face and carrying a depending stud 20 that is swiveled in the rear end of the sight arm as clearly shown in Fig. 3, one side of the screw head 17 being provided with rack teeth 21 meshing with the teeth 13 upon the laterally variable sight. To retain the sight 90 6 in its adjusted positions, a set screw 22

threaded through the opening 23 formed in the base plate 6 of the sight, as shown in Fig. 5, engages the bottom wall of the sight pocket 14 as shown in Fig. 3 for anchoring the same in its adjusted position.

From the above detailed description of the device, it is believed that the construction and operation thereof will be readily understood, it being noted as illustrated in Fig. 1, that the upper face of the rear end 5 of the sight arm and the rear edge of the upper face of the base plate 6 that is exposed, are provided with gage marks 24 that indicate proper alignment of the sight when laterally shifted. To adjust the sight, a screw driver or similar implement is employed for rotating the screw head 17 in the desired direction, thereby transmitting transversely sliding movement to the variable sight as will at once be obvious from an inspection of Figs. 1 and 3.

While there is herein shown and described the preferred embodiment of the present invention, it is nevertheless to be understood that minor changes may be made therein without departing from the spirit and scope of the invention as claimed.

What is claimed as new is:

1. In a laterally variable gun sight, a sight arm fixed at its forward end to a gun barrel, means for raising and lowering the rear end of the sight arm, the rear end of

the arm having a transverse groove therein, a sight wall having a base plate slidable in the groove, a series of rack teeth formed on one edge of the base plate, a disk rotatable in the sight arm and having peripheral teeth engaging the rack teeth, said disk having a kerf-slot in the upper side thereof to facilitate operation in laterally shifting the sight wall, and a set screw carried by the base plate adapted to engage the sight arm to hold the sight wall in adjusted position.

2. In a laterally variable gun sight, a sight arm having an end provided with a transverse groove with undercut sides, a sight wall having a base plate fitting and slidable in the groove, said base plate having rack teeth on one edge, said arm having a recess in its upper face communicating with the groove and further having a frusto-conical recess in its lower face opening concentrically into the first recess, a gear housed entirely in the first recess and meshing with said rack, the upper face of the gear being flush with the upper face of the arm and having a screw kerf, and a frusto-conical stub shaft on said gear held in said second recess to retain the gear in position.

In testimony whereof I affix my signature.

ULRICH VOSMEK.
